(57) **CLAIM**

The ornamental design for a toy radio, as shown and described.

DESCRIPTION

FIG. 1 is a perspective view of a toy radio showing my new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is bottom plan view thereof; and,

FIG. 7 is a top plan view thereof.

The broken lines represent portions of the design that form no part of the claim.
